Attorney, Agent, or Firm—William B. Kircher

[57] **CLAIM**

The ornamental design for a police radar detector, as shown and described.

DESCRIPTION

FIG. 1 is a perspective view of the police radar detector showing our new design;

FIG. 2 is a front elevational view of the detector shown in FIG. 1;

FIG. 3 is a side elevational view of the detector shown in FIG. 1;

FIG. 4 is a rear end elevational view of the detector shown in FIG. 1;

FIG. 5 is a top plan view of the detector shown in FIG. 1; and

FIG. 6 is a bottom plan view of the detector shown in FIG. 1.
